UNITED STATES PATENT OFFICE

HARRY SCHLESINGER, OF DES MOINES, IOWA

PLAIT-HOLDING DEVICE

Application filed July 11, 1932. Serial No. 291,730.

The object of my invention is to provide a plait holding device adapted to be used in combination with an ironing board, the device itself being of simple, durable and comparatively inexpensive construction.

A further object is to provide a device designed for holding plaits in a skirt or the like after the plaits have been arranged by hand, whereby they are held in proper position for being pressed.

More particularly, it is my object to provide a supporting frame in combination with an ironing board with a plait holding device slidably mounted on the frame and a plurality of plait retaining devices also slidably mounted on the frame.

Still a further object is to provide the plait holding device in the form of a bar having a plurality of spring pressed holding members, each of which is independently adapted to engage several plaits of the entire skirt after such plaits have been arranged by the hands of the operator and to thereafter retain these plaits in position by the plait retaining devices. The plaits of the skirt may then be pressed without danger of their being pressed out of position.

With these and other objects in view, my invention consists in the construction, arrangement and combination of the various parts of my device, whereby the objects contemplated are attained, as hereinafter more fully set forth, pointed out in my claims and illustrated in the accompanying drawings.

Although the invention is susceptible of a variety of embodiments, it is unnecessary to fully describe and illustrate more than one in order to give a full understanding of the invention both from its structural and functional standpoints. Accordingly, I have illustrated a preferred and desirable embodiment of the invention in the accompanying drawings in which:

Fig. 1 is a plan view of my device showing it assembled in connection with an ironing board, such as the type generally used in dry cleaning establishments for the pressing of skirts and the like.

Fig. 2 is a side elevation of the same.

Fig. 3 is an enlarged sectional view taken

on line 3-3 of Fig. 2 and illustrating the plait holding device.

Fig. 4 is an enlarged sectional view taken on the line 4-4 of Fig. 2 and illustrating the supporting frame and its manner of connection to the ironing board.

Fig. 5 is an enlarged sectional view on line 5-5 of Fig. 2, illustrating one of the plait retaining means.

Fig. 6 is an enlarged detail sectional view taken on the line 6-6 of Fig. 2 and illustrates several of the holding members of the holding device in operation.

Fig. 7 is a sectional view on the line 7-7 of Fig. 6.

Fig. 8 is a perspective view of one of the holding members.

On the accompanying drawings, I have used the reference character A to indicate generally, a supporting frame. The frame A consists of a U-shaped member 10 provided with suitable braces 12. The arms of the U-shaped member 10 are slidably mounted in sleeves 14.

The supporting frame A also includes a pair of side bars 16 having downturned ends 18, which are also slidably mounted in the sleeves 14. Set screws 20 serve to retain the sleeves 14 frictionally on the coating ends of the member 10 and the downturned arms 18 of the frame A. By this construction, the height of the side members 16 is adjustable.

An inverted U-shaped bar 22 is secured to the side members 16 opposite the downturned ends 18 thereof. The member 22 is adapted to extend over an ironing board B adjacent the support 24 therefor and engage the top of the ironing board, as clearly shown in Fig. 4. The support 24 is illustrated secured to a wall 26 and the U-shaped member 10 rests on the floor 28 of the pressing room.

Clamping clips 30 are slidably mounted relative to the bar 22 and are held in any adjusted position by means of bolts 32 and wing nuts 34. The clamps 30, being slidably mounted, adapt the frame A for connection to ironing boards of various widths.

A supporting bar 36 having an inturned hook 38 at one end and an outturned hook

40 at the other end is adapted to extend under the ironing board B in spaced relation to the bar 22. The supporting bar 36 is adapted to have its hook ends 38 and 40 extend over the side bars 16, as clearly shown in Fig. 4, whereby it is removably attached to the supporting frame A. A pair of set screws 42 having swivel heads 44 for engaging the under surface of the board B are screw threadedly mounted relative to the supporting bar 36.

In assembling the frame A relative to the ironing board B, the sleeves 14 are first adjusted for obtaining the proper height for the frame A for the particular ironing board B to which it is being secured. The clips 30 are then adjusted for engaging the sides of the ironing board. The set screws 42 are then tightened after the supporting bar 36 has been placed in position and the set screws 42 serve to exert an upward pressure on the bottom of the board B for supporting the outer end thereof. By the use of the frame A, no other support is needed for the ironing board B except the one point of fastening to the wall 26 at 24.

Slidably mounted on the members 16 are U-shaped clips 46 having pins 48 rigidly secured thereto. A channel-shaped plait holding bar 50 is provided with openings 52, whereby the bar may be mounted on the pins 48 for vertical sliding movement. Clutch levers 54 are hingedly mounted at 56 on the ends of the bar 50 and are provided with openings 58 adapted to surround the pins 48. A spring 60 is provided for each clutch lever 54 for causing the edge of the opening 58 to bind on the pin 48. The clutch levers 54 allow the plait holding bar 50 to be positioned on the pins 48 and pushed downwardly relative thereto, but prevent them from being raised upwardly except when the clutch levers 54 are moved upwardly relative to the bar 50 by the fingers of the operator. A collar 62 is provided on each pin 48 to limit downward movement of the bar 50 as desired.

A series of openings 64 are provided in the top of the holding bar 50. A series of pins 66 extend through the bar 50 from side to side. Plait holding members C are slidably mounted for vertical movement relative to the bar 50 and comprise block-like portions 68 slidably mounted between the pins 66, as clearly shown in Fig. 6 of the drawings.

Each holding member C is provided with handle portions 70 which are slidably mounted in the openings 64 of the bar 50. Notches 72 are formed in the handle portions 70. A recess 74 is provided in each block-like portion 68 and a spring 76 is inserted in each recess and rests against the under side of the web of the holding bar 50. Flanges 78 are provided on the holding members C to limit their upward movement. The operation and further details of construction of the holding

members C will hereinafter be more fully described.

In connection with the supporting frame A, I provide a plurality of plait retaining devices D. Each retaining device D consists of supporting brackets 80, having openings 82 to receive the side bars 16 of the frame A, whereby the brackets 80 are slidably mounted on the frame A. Extending from the bracket 80 on one of the side members 16 to a bracket 80 on the other side member 16 is a flat resilient bar 84. On my drawings, I have shown three of the plait retaining devices D and they are all similar. Therefore, I will need to describe but one of them.

The retaining bar 84 is normally curved as indicated in dotted lines in Fig. 5 and has one end provided with an eye 86 and its other end provided with a slideable latch 88. A pin 90 serves to hingedly connect the eye 86 to one of the brackets 80 and the pin 90 is removable for selectively coacting with spaced openings 92 in the bracket 80 to which the bar 84 is hinged. The opposite bracket 80 is provided with a plurality of pins 92 with either of which the slideable latch 88 may coact by sliding the latch 88 in the direction of the arrow 94 to the dotted line position shown in Fig. 5. By the construction just described, the bar D may be adjusted up or down for giving it the desired pressure on the board B. When released, the resilient retaining bar 84 will assume its normally curved position and may be raised to a position out of the way, as indicated at 84a.

Practical operation

In the operation of my device, a skirt E or a waist or other plaited article is laid on the ironing board B and the top of the skirt held by one of the plait retaining devices D. Although I have illustrated the skirt as a plaited strip of cloth, the portion of the skirt not on top of the board B would extend under the board in the same manner as when not using my device. In Fig. 1, the left hand retaining device D is the one which holds the upper end of the skirt E. The other two retaining devices D are then moved to a position out of the way and the holding bar 50 used to hold the plaits at the center of the skirt.

The skirt of course, is already plaited, it having been plaited by machine when originally made. When the skirt is cleaned, the plaits partly come out, but are still in well enough to be accurately laid by hand before being pressed. The operator then starts to lay the plaits, as shown in the left hand end of Fig. 6 and when he has three or four of the plaits laid, he moves the handle portion 70 of the holding member C closest to him in the direction of the arrow 9, which causes the notch 72 to disengage from the edge of the opening 64 for allowing the spring 76 to force the holding member C downwardly

against the plaits which have already been folded by hand.

The released member C imposes a sufficient spring tension on the plaits thereunder to hold them in position while the operator proceeds with laying other plaits. In laying the other plaits, he moves each of the handles 70 in the direction of the arrow 96 for releasing the plait holding members successively as the plaits are folded. After the plaits of the portion of the skirt E on top of the board B have been held in the manner just described, the collars 62 may be adjusted downwardly, after which the bar 50 may be pushed downwardly for holding the plaits positively by coaction of the clutch levers 54 with the pins 48 and this pushing down of the bar 50 will reset the plait holding members C in their raised position relative to the bar 50, as shown by the two right hand members C in Fig. 6.

The middle retaining device D is then clamped in position on the plaits being held by the holding bar 50, whereupon the bar is moved to the position illustrated in Fig. 1 with the third retaining device in a raised position, out of the way. The plaits at the bottom of the skirt are then held by the holding devices C in the same manner that they were held at the center of the skirt, as has just been described.

The remaining retaining member D is now moved to position by the side of the holding bar 50 and lowered for retaining the plaits in their plaited position, after which the clutch levers 54 are manipulated for removing the bar 50 or allowing it to be slid longitudinally on the frame A to a position out of the way. The bar 50 is moved in the manner just described and the retaining member D utilized for holding the plaits so that the operator can conveniently press the skirt E between the retaining bars D without the holding bar 50 interfering with his pressing iron in any way.

The retaining bars D are each provided with a downwardly depressed rib 85 adjacent one edge so that they may engage the plaits of the skirt close to the holding bar 50 when moved adjacent thereto. The left hand bar 50 D may be raised and the skirt stretched lengthwise before pressing for the purpose of preventing buckling of the skirt during the pressing operation.

The bar 22 engaging the top of the board 55 B and the set screws 42 engaging the bottom thereof, provide a frame which rigidly supports the board in a predetermined relation with respect to the plait holding and plait retaining devices and only one adjustment is 60 originally necessary for fitting the frame to any board of a given height.

The bar 50 can be arranged on a vertically or horizontally disposed hinge pin if desirable, so that it can be swung out of the way 65 instead of being lifted off the pins 48.

Each plait holding member C is cut away as at 69 to insure that the members C will assume a vertical position when in either a raised or a lowered position. The springs 76, being mounted off center, tend to rotate the member C in a clockwise direction for causing the notches 72 to engage the edges of the openings 64. The cutaway portions 69 also aid in causing such engagement.

It is obvious of course, that various changes such as providing a different type of holding device to replace the bar 50, can be made without departing from the real spirit and purpose of my invention. Also, other retaining devices D could be utilized in the combination and it is my purpose to cover by my claims, such modified forms of construction or use of mechanical equivalents as may be reasonably included within their scope.

Having thus described my invention, what I claim is:—

1. A plait holding device comprising a bar, a plurality of plait holding members movably mounted thereon and individually spring pressed to engage a plurality of plaits, each holding member including a handle, openings in said bar through which said handles slidably extend and notches in said handles to engage the edges of said openings for thereby retaining the holding members in raised position whereby they may be released by disengaging the notches from the edges of said openings.

2. In combination with an ironing board having one end rigidly supported, a frame 100 adapted to engage the top of said board adjacent the supported end thereof and to engage the bottom of said board substantially spaced from the supported end thereof, said frame extending longitudinally along the sides of and spaced from said board and terminating in supporting legs and a plurality of plait engaging members supported on said frame and longitudinally slidable on the portion of the frame arranged along the sides of the board.

3. In combination with an ironing board secured at one end to a rigid support, a plait holding device comprising a frame supported at one end and having its other end clamped to the board adjacent the supported end thereof whereby the free end of the board is supported by said frame in conjunction with said rigid support and plait holding means supported by said frame and extending across said board.

4. In combination with an ironing board having one end rigidly supported, a frame 125 adapted to engage the top of said board adjacent the supported end thereof and to engage the bottom of said board substantially spaced from the supported end thereof, said frame extending longitudinally along the sides of and spaced from said board and terminating in supporting legs, and a plurality 130

of plait engaging members supported above said board by said frame and adapted to engage the plaits of a garment on said board.

5. In combination with an ironing board, a plait holding device comprising a stationary member, means for supporting the same above an ironing board, a plurality of movable members supported thereby and each adapted to independently move downwardly 10 from said stationary member and engage certain plaits of a plurality of plaits, and a retaining device comprising a downwardly bowed bar supported at its ends and adapted to hold all of the plaits after being engaged 15 by said holding device.

6. In combination with an ironing board, a frame having side members arranged longitudinally adjacent said board, a plait holding device and a plurality of plait retaining devices mounted on said side members and extending across said board above the upper surface and independent of the edges thereof, said plait holding device comprising a member having a plurality of sections, each 25 section being adapted to hold certain plaits of a plurality of plaits.

7. In combination with an ironing board, a supporting frame and a plurality of plait holding devices mounted on said frame and 30 extending across said ironing board for holding the plaits of a garment placed on the ironing board, one of said devices being made in independent spring-pressed sections, each having a latch member, said last mentioned 35 device having a portion to coact with each section for latching the latch members in non-operative position, whereby when the sections are unlatched they will thereafter move to position for resilient engagement 40 with the plaits.

8. In combination with an ironing board and a frame associated therewith having side bars spaced from the sides of said board, a pair of members slidably mounted on said 45 side bars and a plait holding device carried by one of said members and detachably connected with the other one, said device extending across the board and being in engagement with the top thereof when the device is 50 connected with said other member.

9. In combination with an ironing board and a frame associated therewith, a plait holding device, means for supporting the ends thereof at a position substantially level 55 with the top of said board, said plait holding device being formed of resilient material and tending to be bowed downwardly when in contact with the board whereby to engage said board with an equal pressure throughout 60 the length of the device.

10. A plait holding device comprising a board, a support fixed relative thereto, a bar carried by said support, a plurality of plait holding members movably mounted on said 65 bar and individually spring pressed toward

the support to engage a plurality of plaits, and releasable catch means for retaining said holding members in non-operative position, said bar being vertically movable relative to said support and said catches being engageable with said board whereby to reset all of said catches simultaneously. 70

11. In combination with an ironing board having a rigid support for one end thereof, means for supporting the other end of said ironing board in extended position, said means comprising a supporting frame, a cross bar thereon positioned above the board adjacent said rigid support, a second cross bar upon said supporting frame positioned beneath said ironing board and spaced outwardly from said first cross bar and set screws carried by one of said cross bars, said set screws being adjustable relative to said cross bar and engageable with said board to 80 secure the supporting frame to the board. 85

Des Moines, Iowa, May 22, 1928.
